AUTOMATIC LIGHT-SELECTOR SYSTEM

William R. Curtiss, Meriden, Conn., assignor to
Air Devices Corporation, Meriden, Conn., a cor-
poration

Application August 1, 1938, Serial No. 222,460

12 Claims.

(Cl. 171—97)

The present invention concerns a novel light-selector system for automatically and selectively controlling light-circuits. More especially, the invention relates to an improved light-selector system operable to automatically initially furnish or to maintain illumination.

One of the objects of this invention is to provide a superior light-selector system having self-acting means operable to initially furnish illumination or to maintain illumination without undue interruption, whereby need for consistent attendance on or observation of a light-system, and undesirable consequences due to lack of such attendance or notice of the operating condition of a light-system, are substantially eliminated.

Another of the objects of the present invention is to provide an improved light-selector system automatically operable to initially furnish or to maintain adequate illumination without noticeable interruption, and thereby materially reduce inconveniences and hazards due to lighting-failures.

A further object of the present invention is to provide a sensitive automatic light-selector system responsive to failure of an illuminating-element of a light-circuit, such as a filament, to automatically cause other illuminating-means to be operated, whereby the failure of the element of a light-circuit which is relatively more susceptible to breaking or burning-out, will cause no appreciable interruption in the operation of the light-system.

Still another object of this invention is to provide for a light-system employing relatively-fragile filaments which are frequently subjected to extreme operating conditions, a superior automatic light-selector arrangement, which is responsive to one of the relatively-frail filaments becoming defective to cause the operation of other illuminating-means, whereby the improved system is peculiarly well suited to maintain illumination under trying operating conditions, and particularly where under conditions as described the avoidance of light-interruption is an essential factor of safety.

Another and further object of the invention is the provision of an automatic light-selector system for the purposes described in which controlling-elements thereof are few in number and may be neatly and compactly assembled to effect space economies, whereby the system may be readily installed in locations where limitations as to available space prevail.

It is also an object of the present invention to provide an automatic light-selector system for

the purposes described which is featured by simplicity and strength with respect to the construction of the parts and the arrangement of the circuits thereof, the absence of involved arrangements providing a system which can be understood, arranged and followed without difficulty, and the parts being amply safeguarded against occurrences of "sneaks," "shorts" or other faults and being accessible as for purposes of checking and testing, whereby maintenance care may be conveniently accomplished and is of minimum degree.

With the above and other objects in view, as will appear to those skilled in the art from the present disclosure, this invention includes all features in the said disclosure which are novel over the prior art.

In the accompanying drawing, in which certain modes of carrying out the present invention are shown for illustrative purposes:

The single figure of the accompanying drawing is a schematic view illustrating the parts and circuits of an automatic light-selector system embodying the present invention, as applied to control headlamps of a vehicle, the system here being shown in its neutral or "off" position;

In the drawing and in the description now about to follow, one form of the light-selector system of the present invention is shown and will be particularly referred to in connection with the control of the lighting of headlamps of a vehicle, such as the headlamps of a motor-vehicle.

The elements of the system apart from the circuit arrangements therefor will be first described and include two spaced headlamps schematically indicated in the drawing within the dotted lines designated by the reference characters 10—10. The headlamps 10—10 are arranged to be illuminated by electric current supplied through suitable circuits from a battery 11. A manual-control switch enclosed in dotted lines and designated as a whole by the reference character 12, is provided for the manual control of the light-circuits. These circuits, as will be understood, are energizable selectively to cause light of relatively-high or of relatively-low intensity to be emitted by the headlamps 10—10, as when the vehicle is being operated with what is known as "bright" or "dim" illumination, by which terms the respective circuits will be designated herein.

For the purpose of maintaining illumination in the event of the failure of a circuit energized by the actuation of the manual-controlled switch, automatically operable change-over mechanism is provided. This change-over mechanism in-

cludes a plurality of relays. The elements of each of the said relays for convenient reference purposes have been enclosed in dotted lines and indicated as individual units, and to each of these 5 units a general reference character has been applied.

As shown, there is provided a pilot-relay, indicated generally by the reference character 13 and a pilot-relay designated as a unit by the reference 10 character 14. The said pilot-relays 13 and 14 are, as will more fully appear, respectively controlled by the "bright"-circuit and the "dim"-circuit of the system.

Controlled by the pilot-relay 13 is a change-over relay designated as a whole by the reference character 15. Similarly there is provided a change-over relay generally designated by the reference character 16, which relay is controlled by the pilot-relay 14.

Preferably here is also provided a tell-tale lamp 17 arranged to be controlled by each of the said change-over relays in such manner as to be illuminated to indicate each operation of the change-over mechanism.

The battery 11 mentioned above is, in the example here being described, located in a motor-vehicle and one of its terminals is suitably grounded therein as by means of the conductor 11a. From the opposite terminal of the said battery 11 a main lead 18 extends to a junction-point 19 where it is connected with branch-leads 20 and 21. The purpose of the branch-lead 20 will be hereinafter described and the purpose of the branch-lead 21 is to electrically connect the manual-control switch 12 with the said battery 11.

For the manual control of the "bright" and "dim" circuits mentioned herein, the schematically-illustrated manual-control switch 12 may comprise a contact-blade or contact-arm 22 to which the adjacent end of the branch-lead 21 is connected. The contact-arm 22 is pivoted at 23 and its opposite end is selectively engageable with contacts 25 and 26. The said contact 25 forms part of the manually-controlled portion of the "bright" circuit, and the said contact 26 comprises part of the manually-controlled portion of the "dim" circuit for the headlamps 10-10, as will presently appear.

Automatic control of the said "bright" and "dim" circuits may be effected by means of the automatic change-over mechanism referred to herein, and which will now be more fully described.

The pivot-relay 13 of the said automatic change-over mechanism includes a core 27 which carries a coil 28, whereby the operation of an armature 29 of the said pilot-relay is controlled. The armature 29 is pivoted at 30 and is normally held away from the core 27 by means of a spring 31, in which position the said armature normally engages a contact 32 of the said pilot-relay.

Similarly, the pilot-relay 14 includes a core 33 about which is wound a coil 34, an armature 35 pivoted at 36 and normally held by means of a spring 37 away from the said core 33 and in engagement with a contact 38 of the said pilot-relay 14.

Associated with each of the pilot-relays 13 and 14 are the change-over relays 15 and 16 respectively. As shown, the change-over relay 15 comprises a core 39 having a coil 40, and an armature 41 pivoted at 42 and normally held away from the core 39 by means of a spring 43. Also

forming part of the change-over relay 15 are contacts 44 and 45 adapted to be engaged by the armature 41 but from which the said armature is normally held separated by the said spring 43.

The change-over relay 16 is similar to the relay 15 and comprises a core 46, a coil 47, an armature 48 pivoted at 49 and normally held from the core 46 by a spring 50. The relay 16 also includes contacts 51 and 52 adapted to be engaged by the armature 48 but away from which the said armature is normally held by the afore-said spring 50.

For effecting illumination of the headlamps 10-10 through the operation of the system, each of the circuits now to be described comprises a filament located in each of the said headlamps. The "bright" circuit includes "bright"-filaments 53-54, respectively included in the headlamps 10-10, and the "dim" circuit includes "dim"-filaments 55-56 also respectively included in the said headlamps 10-10. As is clearly shown, the bright-filament 53 and the dim-filament 55 in one of the headlamps 10 are connected together at a common junction-point 57 and to a ground 58. In like manner the other bright-filament 54 and the other dim-filament 56 are connected together at one end thereof to a common junction-point 59 and ground 60.

Each of the circuits referred to is a multiple-circuit comprising normally-open paralleling-portions. One of the normally-open paralleling portions of each of the circuits is manually controlled by the manual-control switch 12 and will be referred to herein as the master-portion thereof, and the other normally-open paralleling portion of each of the circuits is automatically controlled by the change-over mechanism, before described, and will be herein referred to as the shunt-portion thereof.

The manually-controlled master-portion of the "bright"-circuit may be traced from the contact-point 25 of the switch 12 through a lead 61 to a terminal-point 62 where it is joined to the portion of the bright-circuit common to the master-portion and the shunt-portion thereof. At the said terminal-point 62 the lead 61 is connected to one terminal of the coil 28 of the pilot-relay 13 which has its other terminal connected to a terminal-point 63. From the said terminal-point 63 the circuit leads by way of a conductor 64 to a terminal-point 65 where it is divided. At the said terminal-point 65 the conductor 64 is connected to one end of the bright-filament 53 of the left headlamp 10, the other end of which filament is grounded at 58. At the terminal-point 65 the conductor 64 is also connected to a branch-lead 66 which at its opposite end is connected at a junction-point 67 to one end of the bright-filament 54 of the right headlamp 10, and the opposite end of the said filament is connected to the ground 60. There is thus provided a grounded circuit which when closed will cause the pilot-relay 13 to become energized and which will also cause the parallelly-connected bright-filaments 53-54 of the said bright-circuit to become incandescent.

It will also be noted that at the said terminal-point 62 there is connected a short-lead 68 leading to a junction-point 69 from which junction-point another short-lead 70 leads to the armature 29 of the said pilot-relay 13, for a purpose to be described. Another lead 71, which as will appear comprises part of the shunt-portion or parallel-portion of the bright-circuit is also con-

nected through the said junction-point 69 and the short-lead 68 to the terminal-point 62, and in this manner the said shunt-portion, together with the described master-portion is joined at 5 the terminal-point 62 to the remaining common portion of the said bright-circuit. The end of the lead 71 opposite its connection to the terminal-point 69 is connected to the contact 51 of the change-over relay 16.

10 The master-portion of the dim-circuit starts at the manual-control switch 12, one end of a lead 72 being connected to the contact 26 of the said switch and the other end of the said lead being connected to a terminal-point 73, at which point 15 the said master-portion is joined to the remaining portion of the dim-circuit which is common to the master-portion and the shunt-portion thereof. At the said terminal-point 73 the lead 72 is connected with one terminal-end of the coil 20 34 of the pilot-relay 14. The circuit leads through the said coil 34 which has its other terminal connected to a terminal-point 74 and along a conductor 75 to a terminal-point 76. At the said terminal-point 76 the circuit is divided by 25 means of leads 77 and 78. The lead 77 is connected at a junction-point 79 with one end of the dim-filament 55 of the left headlamp 10. The opposite end of the said dim-filament is connected to the common junction-point 57 and hence 30 to the ground at 58. The other lead 78 is connected at a junction-point 80 with one end of the dim-filament 56 of the right headlamp 10, which filament is connected at the common junction-point 59 to the ground 60. In this manner, 35 another grounded circuit is provided which is operable to cause energization of the pilot-relay 14 and to cause the dim-filaments 55 and 56 to become incandescent.

In a similar manner to that described in connection with the bright-circuit, the terminal-point 73 in the dim-circuit is connected by a short-lead 82 to a junction-point 81 and from the latter another short-lead 83 is connected to the armature 35 of the said pilot-relay 14. Also 45 connected to the said terminal-point 73 through the said junction-point 81 and the short-lead 82 is one end of a lead 84 extending to the contact 44 of the relay 15 and forming part of the shunt-portion or paralleling-portion of the dim-circuit 50 which is in this manner joined with the master-portion of the said circuit and with the remaining common portion of the said dim-circuit.

As has been referred to herein at the junction-point 19 of the lead 18 from the battery 11, there 55 is connected a branch-lead 20. This branch lead 20 serves as a common lead comprising another part of the shunt-portion or paralleling-portion of each of the said circuits.

At a junction-point 85 along the said common-lead 20 there is connected a short-lead 86 which at its opposite end is connected to the armature 48 of the change-over relay 16 whereby the said armature is at all times electrically connected to the battery 11. The said armature 48 as has been 60 described is normally separated from the contacts 51 and 52 of the said change-over relay 16. The contact 51 of the said contacts is connected to the end of the lead 71 opposite the end thereof of which at the junction-point 69 is connected by the short-lead 70 to the armature 29 of the pilot-relay 13, and which through the short-lead 68 is connected to the terminal-point 62 and thus joined to the said common-portion of the bright-circuit.

75 From the junction-point 85 above referred to,

the said common-lead 20 is continued to and connected with the armature 41 of the change-over relay 15, whereby the said armature 41 is also at all times electrically connected to the battery 11. The armature 41 as before described is normally separated from the contacts 44-45 of the said change-over relay 15, the contact 44 of which is connected to one end of the lead 84. The opposite end of the said lead 84, as has been described, is connected at the junction-point 81 to 10 the short-lead 83 to the armature 35 of the pilot-relay 14, and by means of the short-lead 82 is also connected to the terminal-point 73 and thereby joined to the said common portion of the dim-circuit.

15 For the purpose of operating each of the said change-over relays to cause its armature to engage the contacts described above, which are normally separated therefrom, an operating-circuit is provided each of which is controlled by one of 20 the said pilot-relays of the change-over mechanism.

Connected to the contact 32 normally engaged by the armature 29 of the pilot-relay 13, is one end of a lead 87 having its other end connected 25 to a terminal-point 88. At the said terminal-point 88 there is also connected one terminal of the coil 40 of the change-over relay 15, and the other terminal-end of the said coil 40 is connected at a terminal-point 89 with a grounded conductor 90.

30 Similarly, the contact 38 which is normally engaged by the armature 35 of the pilot-relay 14 is connected to one end of a lead 91 which at its other end is connected to a terminal-point 92. 35 To this terminal-point 92 one terminal of the coil 47 of the change-over relay 16 is connected, and the other terminal of the said coil is connected at a terminal-point 93 with a grounded conductor 94.

40 The contacts 45 and 52 of the respective change-over relay 15 and 16, which are normally separated from but are on occasion engageable by the armatures 41 and 48 respectively, are connected to one end of conductors 95 and 96 respectively. The said conductors 95 and 96 are joined at a junction-point 97 to a common-lead 98 extending to one terminal of the aforesaid tell-tale lamp 17 which latter has its other terminal connected to a grounded conductor 99. In 50 this manner the operation of either the change-over relays 15 or 16 will be indicated by the illumination of the said tell-tale lamp 17.

55 In operation, the movement of the contact-blade 22 of the manual-control switch 12 into engagement with the bright-contact 25, for example, will close the normally-open, manually-controlled master-portion of the bright-circuit. Current will then pass from the battery 11 through main-lead 18, junction-joint 19 and lead 60 21 to the contact-blade 22, and thence through the contact-point 25 along the lead 61 to the junction-point 62. From the junction-point 62 current will flow through the coil 23 of the pilot-relay 13 to the junction-point 63 and thence 65 along the conductor 64 to the terminal-point 65 with the result that the armature 29 is pulled away from the contact 32 (Fig. 2). At the said terminal point 65 the current will be divided and a portion will pass through the "bright"-filament 70 53 in the left headlamp 10 to the junction-point 57 and thence to ground 58. The remaining portion of the current will pass along the lead 66 to the junction-point 67, thence through the "bright"-filament 54 in the right headlamp 10 to 75

ground 60 by way of the junction-point 59. The bright-circuit will thus be completed to cause the pilot-relay 13 to become energized, and to also cause the bright-filaments 53 and 54 to become incandescent whereby a bright beam will be emitted from each of the headlamps 10.

At the said junction-point 62 a part of the current flowing in the above-described circuit will seek a path by way of the lead 68 and junction-point 69 along the conductor 71, and also through the lead 73 to the armature 29 of the pilot-relay 13. This will be without effect, since at this time the path along the conductor 71 will be open at the contact 51 of the relay 16 and will be open at the contact 32 of the pilot-relay 13, as will be seen by reference to Fig. 2.

With the parts acting as above described the respective bright-filaments 53 and 54 of the headlamps 10—10 will be energized in the usual way. For the purpose of description, let it now be presumed that the bright-filament 53 of the left headlamp 10 has been burned out or otherwise ruptured.

Instantly that either or both of the bright-filaments 53 or 54 is ruptured the voltage of the current flowing through the coil 28 of the pilot-relay 13 will, of course, drop, whereupon the spring 31 of the said pilot-relay 13 will act to swing the armature 28 up into engagement with the contact 32 whereupon current will flow from the junction-point 69 to the armature 29, contact 32 and thence through the coil 40 of the change-over relay 15. The flow of current as just described, through the coil 40 will cause the armature 41 of the change-over relay 15 to move into engagement with both of the contacts 44 and 45 of the said change-over relay 15 to thereby energize the tell-tale lamp 17 and cause the current to flow from the conductor 20 to the conductor 64, junction-point 81, conductor 82, junction-point 73, thence through the coil 34 of the pilot-relay 14, and downward through the junction-point 74, conductor 75 and the two-conductors 77 and 78, thereby supplying energy to both of the dim-filaments 55 and 56 respectively of the left and right headlamp 10—10. At the time that current flows through the coil 34 of the pilot-relay 14 as just described, in order to reach the dim-filaments 55 and 56, the coil 33 of the pilot-relay 14 will be magnetized and cause the attraction of the armature 35 thereby drawing the latter away from the contact 38, so that at this time current is not supplied to the change-over relay 16.

With the parts in the positions just above described, both of the dim-filaments 55 and 56 are energized and the remaining unbroken bright-filament 54 also remains energized. The lighting of the tell-tale lamp 17 will immediately advise the operator that one or more of his bright-filaments have ruptured, whereupon ordinarily the operator would manually-operate the manual-control switch 12 so as to directly couple in the dim-filaments 55 and 56 and avoid having the right headlamp showing both a dim and a bright-filament. If, however, the operator of the vehicle chooses to ignore the signal given by the tell-tale lamp 17 both of the dim-filaments 55 and 56 will remain energized as will also the unbroken bright-filament 54.

Having described above the occurrence which takes place when the operator initially chooses to operate on the bright-filaments 53 and 54, and what occurs when one of the said filaments (the bright-filaments 53) is ruptured, let it now

be assumed, that initially the operator chose to energize both of the dim filaments 55 and 56. This the operator would accomplish by turning the manual-control switch 12 to engage the arm 22 thereof with the contact 26. It will be noted that by the manipulation of the manual-control switch 12 to select initially the energization of the dim-filaments 55 and 56, the pilot-relay 14 becomes energized as well as both of the dim-filaments 55 and 56, both of which latter are dependent for their current supply upon the current flowing through the coil 34 of the said pilot-relay 14.

The simultaneous energization of the pilot-relay 14 and the dim-filaments 55 and 56 will be accompanied by the movement of the armature 35 away from the contact 38, thereby preventing the energization of the change-over relay 16.

For the purpose of further making clear the operation of the improved light-selector system of the present invention, let it now be assumed that the dim-filament 55 of the left head-lamp 10 becomes ruptured for some reason.

The rupture of the dim-filament 55, as described (or the rupture of the dim-filament 56, or of both dim-filaments) will occasion a voltage drop in the coil 34 of the pilot-relay 14, thereby enabling the spring 37 to draw the armature 35 of the said pilot-relay upwardly into engagement with the contact 38. This engagement of the armature 35 with the contacts 38 will cause the energization of the change-over relay 16. The energization of the change-over relay 16, as just described, will cause the armature 48 thereof to be drawn downwardly into engagement with both of the contacts 51 and 52, thereby simultaneously energizing the tell-tale lamp 17 by means of the contact 52 and both of the bright-filaments 53 and 54 by means of current supplied by way of the contact 52, the conductor 72, the coil 28 of the pilot-relay 13 and the conductors connected thereto.

Under the conditions just above described, both of the bright-filaments 53 and 54, as well as the unruptured dim-filament 56 of the right head-lamp 10, will be energized and the tell-tale lamp 17 will advise the operator of the vehicle that one of the filaments has been ruptured.

From the foregoing, it will be seen that by means of the automatic light-selector system of the present invention, when either or both of the bright-filaments 53 and 54 become ruptured, the system will shift over and automatically energize the dim-filaments 55 and 56 and will simultaneously advise the operator of the vehicle, by means of the tell-tale lamp 17, that a rupture has occurred. Conversely, and in substantially the same manner, should the operator have initially chosen to energize the dim-filaments 55 and 56 and should either or both thereof become ruptured, the system will automatically cause the energization of the bright-filaments 53 and 54 and similarly advise the operator of the occurrence of a rupture by the illumination of the tell-tale lamp 17.

It will be clear from the foregoing description of the arrangement and operation of the system of the present invention, that when the manually-controlled master-portion of either of the light-circuits is closed to complete the circuit, a pilot-relay controlled by the circuit is energized and attracts its armature to open-circuit the change-over relay which controls the shunt-portion of the other light-circuit. Thus the master-portion of one circuit and the shunt-portion of the other circuit cannot be closed at the same

time and the two light-circuits, therefore, cannot be inadvertently or unintentionally energized at the same time.

Also, it will be observed that when either of the light-circuits becomes defective and current passing therethrough causes a change-over relay to function to close the shunt-portion of and thus complete the other light-circuit, that the pilot-relay of the light-circuit thus completed will operate to open-circuit the change-over relay controlling the shunt-portion of the defective circuit. By this arrangement the manually-controlled master-portion and the automatically-controlled shunt-portion of the same light-circuit cannot be closed at the same time.

The provision of a pilot-relay and a change-over relay for each of the light-circuits makes it possible to employ simple and direct circuits which are free of complications. This removes causes of shorts, sneaks and other faults and enables the system to be readily installed and to be fully accessible for checking or the like.

The above and other apparent advantages of the light-system of the present invention do away with objectionable conditions which, resulting in failure or improper functions of elements, may cause an automatic light-system of itself to be the responsible cause of lighting-failures.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An automatic light-selector system comprising: a source of current-supply; illuminating-means operable therefrom; normally-open light-circuits for connecting the current-supply with the illuminating-means; a circuit-closer device operable to selectively close any of the light-circuits; and self-acting change-over mechanism arranged to continuously maintain the respective light-circuits electrically-independent and including a change-over relay for each light-circuit, operating-means for each change-over relay controlled by another of the electrically-independent light-circuits; one of the said operating-means being responsive to failure in a portion of one side of a first, selectively operated light-circuit to close an operating-circuit for the change-over relay for a second light-circuit, the said operating-circuit being electrically-independent of the said second light-circuit, and the change-over relay thereby energized operating to actuate contact-means thereof to automatically close the said second electrically-independent light-circuit and operate other illuminating-means.

2. An automatic light-selector system comprising: a source of current-supply; illuminating-means operable therefrom; normally-open light-circuits for connecting the current-supply with the illuminating-means; a circuit-closer device operable to selectively close any of the light-circuits; and self-acting change-over mechanism arranged to continuously maintain the respective light-circuits electrically-independent and including change-over relay-means, pilot-relays controlling the change-over relay-means, one of the pilot-relays being operably-controlled by each electrically-independent light-circuit, and each pilot-relay comprising operating-means for said

change-over relay means; one of the said pilot-relays being responsive to failure in a portion of one side of a first-selectively operated light-circuit to cause its said operating-means to close an operating-circuit for the change-over relay-means, the said operating-circuit being electrically-independent of a second light-circuit, and the change-over relay-means thereby energized acting to operate contact-means thereof to automatically close the second electrically-independent light-circuit and operate other illuminating-means.

3. An automatic light-selector system comprising: a source of current-supply; illuminating-means operable therefrom; normally-open light-circuits for connecting the current-supply with the illuminating-means; a circuit-closer device operable to selectively close any of the light-circuits; and self-acting change-over mechanism arranged to continuously maintain the respective light-circuits electrically-independent and including a change-over relay for each electrically-independent light-circuit, a pilot-relay in each electrically independent light-circuit controlling a change-over relay for another of the electrically independent light-circuits, and each pilot-relay having an armature and contact-means comprising operating-means for one of the said change-over relays; one of the said pilot-relays being responsive to failure in a portion of a first, selectively operated light-circuit for causing the armature and contact-means thereof to close an operating-circuit for the change-over relay for a second light-circuit, the said operating-circuit being electrically-independent of the said second light-circuit and the thereby operated change-over relay actuating contact-means thereof to automatically close the said second electrically-independent light-circuit to operate other illuminating-means.

4. An automatic light-selector system comprising: a source of current-supply; illuminating-means operable therefrom; normally-open light-circuits for connecting the current-supply with the illuminating-means; self-acting change-over mechanism arranged to continuously maintain the respective light-circuits electrically-independent and including a change-over relay for each light-circuit, and pilot-relays each having a coil and armature in circuit with one of the electrically-independent light-circuits, the armature and normally engaged contact-means of each pilot-relay comprising part of an operating-circuit for one of the said change-over relays, and each of the change-over relays controlled by one of the pilot-relays having an armature in circuit with a portion of another one of the said electrically-independent light-circuits and contact-means normally separated from the armature; a circuit-closer device operable to selectively close any of the light-circuits to operate illuminating-means and to cause the pilot-relay therein to open-circuit the change-over relay controlled thereby; one of the said pilot-relays being responsive to failure in a portion of one side of a first, selectively operated light-circuit for causing the armature and contact-means of the said pilot-relay to reclose the operating-circuit for the change-over relay, for a second light-circuit, the said operating-circuit being electrically-independent of the said second light-circuit and the armature and contact-means of the thereby operated change-over relay operating to automatically close the said second electrically-independent

ent light-circuit to operate other illuminating-means.

5. An automatic light-selector system comprising: a source of current-supply; illuminating-means operable therefrom; light-circuits, each including normally-open master and shunt-portions, each of the light-circuits being operable to electrically connect the current-supply with a plurality of illuminating-devices; and self-acting 10 change-over mechanism arranged to continuously maintain the respective light-circuits electrically-independent and including a single change-over relay for each electrically-independent light-circuit, operating-means for solely controlling each change-over relay and in turn controlled by another of the electrically-independent light-circuits; one of the said operating means being responsive to failure in a portion of one side of a first operated light-circuit to close 15 an operating-circuit for the change-over relay for a second light-circuit, the said operating-circuit being electrically-independent of the said second light-circuit, and the change-over relay thereby energized operating to actuate contact-means 20 thereof to close the shunt portion of and thereby automatically complete the said second of the electrically-independent light-circuits to operate the said plurality of illuminating-devices controlled thereby.
- 25 6. An automatic light-selector system comprising: a source of current-supply; illuminating-means operable therefrom; light-circuits, each including normally-open master and shunt-portions, each of the light-circuits being operable to 30 electrically connect the current-supply with a plurality of illuminating-devices; a circuit-closer device operable to selectively close any of the master-portions to operate a plurality of the said illuminating devices; and self-acting change-over mechanism arranged to continuously maintain the respective light-circuits electrically-independent and including change-over relay-means, pilot-relays solely controlling the change-over relay-means, one of the pilot-relays being 35 operably-controlled by each electrically-independent light-circuit and each pilot-relay comprising operating-means for said change-over relay means; one of the said pilot-relays being responsive to failure in a portion of one side of a 40 first, selectively operated light-circuit to cause its said operating-means to close an operating-circuit for the change-over relay-means, the said operating-circuit being electrically-independent of a second light-circuit, and the change-over 45 relay-means thereby energized acting to actuate contact-means thereof to close the shunt-portion of and thereby automatically complete the said second of the electrically-independent light-circuits to operate the said plurality of illuminating-devices controlled thereby.
- 50 7. An automatic light-selector system comprising: a source of current supply; illuminating-means operable therefrom; light-circuits, each including normally-open master and shunt-portions, each of the light-circuits being operable to 55 electrically connect the current-supply with a plurality of illuminating-devices; a circuit-closer device operable to selectively close any of the master-portions to operate a plurality of the said illuminating-devices; and self-acting change-over mechanism arranged to continuously maintain the respective light-circuits electrically-independent and including a single change-over relay for each electrically-independent light-circuit, a single pilot-relay in each electrically-independent 60

light-circuit solely controlling the change-over relay of another of the electrically-independent light-circuits and each pilot-relay having an armature and contact-means comprising operating-means for one of the said change-over relays; one of the said pilot-relays being responsive to failure in a portion of one side of a first, selectively operated light-circuit for causing the armature and contact-means thereof to be actuated to close an operating-circuit for the change-over relay for a second light-circuit, the said operating-circuit being electrically-independent of the said second light-circuit and the thereby-operated change-over relay operating contact-means thereof to close the shunt-portion of and thereby automatically close the said second of the electrically-independent light-circuits to operate the said plurality of illuminating-devices controlled thereby.

20 8. An automatic light-selector system for headlamps comprising: a source of current-supply; normally-open light-circuits for connecting the current-supply with the headlamps, each of the said light-circuits including a filament located in each of two separated headlamps; a switch manually-operable to selectively close a light-circuit to cause incandescence of the filaments thereof; and self-acting change-over mechanism arranged to continuously maintain the respective light-circuits electrically-independent and including a single change-over relay for each electrically-independent light-circuit, operating-means for solely controlling each change-over relay and in turn controlled by another of the 25 electrically-independent light-circuits; one of the said operating-means being responsive to failure of a filament in a first, selectively operated light-circuit to close an operating circuit for the change-over relay for a second light-circuit, the said operating-circuit being electrically-independent of the said second light-circuit, and the change-over relay thereby energized operating to actuate contact-means thereof to automatically close the said second electrically-independent light-circuit and cause the filament thereof in 30 each of the said headlamps to become incandescent.

35 9. An automatic light-selector system for headlamps comprising: a source of current-supply; normally-open light-circuits for connecting the current-supply with the headlamps, each of the said light-circuits including a filament located in each of two separated head-lamps; a switch manually-operable to selectively close a light-circuit to cause incandescence of the filaments thereof; and self-acting change-over mechanism arranged to continuously maintain the respective light-circuits electrically-independent and including change-over relay-means, pilot relays solely controlling the change-over relay-means, one of the 40 pilot-relays being operably-controlled by each electrically-independent light-circuit, and each pilot-relay comprising operating-means for said change-over relay means; one of the said pilot-relays being responsive to failure of a filament in a first, selectively operated light-circuit to cause its said operating-means to close an operating-circuit for the change-over relay-means, the said operating-circuit being electrically-independent of a second light-circuit, and the change-over 45 relay-means thereby energized acting to operate contact-means thereof to automatically close the said second electrically-independent light-circuit and cause the filament thereof in each of the headlamps to become incandescent.

10. An automatic light-selector system for head-lamps comprising: a source of current-supply; normally-open light-circuits for connecting the current-supply with the headlamps, each of the said light-circuits including a filament located in each of two separated head-lamps; a switch manually-operable to selectively close a light-circuit to cause incandescence of the filaments thereof; and self-acting change-over mechanism arranged to continuously maintain the respective light-circuits electrically-independent and including a single change-over relay for each light-circuit, a single pilot-relay in each electrically-independent light-circuit solely controlling the change-over relay for another of the light-circuits, and each pilot-relay having an armature and contact-means comprising operating-means for one of the said change-over relays; one of the said pilot-relays being responsive to failure of a filament in a first, selectively operated light-circuit for causing the armature and contact-means thereof to close an operating-circuit for the change-over relay for a second light-circuit, the said operating-circuit being electrically-independent of the said second light-circuit and the thereby operated change-over relay operating contact-means thereof to automatically close the said second electrically-independent light-circuit and cause the filament thereof in each of the said headlamps to become incandescent.

11. An automatic light-selector system for head-lamps comprising: a source of current-supply normally-open light-circuits for connecting the current-supply with the headlamps, each including a filament located in each of two separated headlamps; self-acting change-over mechanism arranged to continuously maintain the respective light-circuits electrically-independent and including a single change-over relay for each electrically-independent light-circuit, and pilot-relays each having a coil and armature in circuit with one of the electrically-independent light-circuits, the armature and normally engaged contact-means of each pilot-relay comprising part of an operating-circuit for one of the said change-

over relays, and each of the change-over relays controlled by a pilot-relay in one of the light-circuits having an armature in circuit with a portion of a different one of the electrically-independent light-circuits and contact-means comprising part of another portion of the said different one of the light-circuits and normally separated from the armature thereof; a switch manually-operable to selectively close a light-circuit to cause the filaments thereof to become incandescent and to cause the pilot-relay in the said light-circuit to open-circuit the change-over relay controlled thereby; one of the said pilot-relays being responsive to failure of a filament in a first, selectively operated light-circuit for causing the armature and contact-means thereof to re-close the operating-circuit for the change-over relay for a second light-circuit, the said operating-circuit being electrically-independent of the said light-circuit and the armature and contact-means of the thereby operated change-over relay operating to automatically close the second electrically-independent light-circuit and cause the filaments thereof in each of the headlamps to become incandescent.

12. An automatic light-selecting system, including in combination: a source of current-supply; first lighting-means; second lighting-means; electrical conductors serving to connect the aforesaid lighting-means with the said source of current-supply; a single pilot-relay connected in series with the first lighting-means and having circuit-controlling means electrically connected with the said first lighting-means and electrically-independent of the said second lighting-means; a single change-over relay electrically connected to the said pilot-relay so as to be controlled by the circuit-controlling means thereof and energized by a circuit electrically independent of the said second lighting-means, the said change-over relay having circuit-controlling means connected to the said second lighting-means for supplying current thereto when the aforesaid pilot-relay fails to receive current due to the failure of the first said lighting-means.
